UNITED STATES PATENT OFFICE

LEWIS E. YOUNIE, OF PORTLAND, OREGON, ASSIGNOR TO ELECTRIC STEEL FOUNDRY COMPANY, OF PORTLAND, OREGON, A CORPORATION OF OREGON

POWER SCRAPER

Application filed April 10, 1930. Serial No. 443,177.

The present invention is designed to improve power scrapers. These scrapers differ somewhat from bottomless scrapers and also from the ordinary drag line buckets. These scrapers are subjected to very severe strains. The ordinary bottomless scrapers act very unsatisfactorily in many materials. The present invention provides such a scraper with laterally extending blades, or shoes cutting the material and turning it inwardly into the space within the scraper much as plows cut and turn the earth acted upon. The scraper is improved by dividing it by a forwardly extending plate on which are provided similar cutting blades, or shoes operating in the manner of the shoes on the main walls of the scraper. Such a projecting plate may be utilized for bracing the arch where an arch is used, the connection not only bracing the arch but bracing the rear wall of the scraper through such connection. Features and details of the invention will appear from the specification and claims.

A preferred embodiment of the invention is illustrated in the accompanying drawing as follows:

Fig. 1 shows a plan view of the scraper.

Fig. 2 a section on the line 2—2 in Fig. 1.

Fig. 3 a front elevation of the scraper.

Fig. 4 a section on the line 4—4 in Fig. 1.

Fig. 5 a section on the line 5—5 in Fig. 1.

The scraper has the sides 1, rear ends 2 and a central dividing member 3, thus providing two compartments 4, 4. The tops of the walls of the scraper are formed by channels 5 which are curved at the rear and united at 6 with the central plate 3, the channels forming what might be described as a heart shape. A plate 7 is secured at the juncture of the channels and is provided with haul-back links, or connections 8.

The walls are extended downwardly by plates 9 which are secured to the channels and at the rear are preferably inclined toward the front of the scraper. All the lower edges of the scraper are provided with shoes. Side shoes 12 are connected through end shoes 13 with shoes 14 extending from the dividing plate. These shoes are slightly inclined upwardly toward the walls and preferably

curved so as to roll the earth as it is cut up into the interior of the scraper. The forward ends of the shoes at the sides have points 11 which preferably extend forward of the scraper proper and also slightly outward so as to cut the material slightly outside of the walls of the scraper and thus reduce the force necessary to operate the scraper. The shoes are also cut out back from their cutting edges at 10. This reduces the ground friction and reduces the metal required. The central shoe terminates in a point 15 which is preferably made in a separate piece so that it may be renewed, if desired. It will also be understood that the shoes, or extensions 11 may also be renewed.

An arch 16, preferably of box form, is secured to the side walls terminating in the upwardly extending portions of the shoes 12. Angle plates 17 connect the plate 3 with the arch. Thus the arch is braced by the plate and the plate connects the rear end of the scraper, thus bracing and stiffening the rear wall.

Ears 18 extend forwardly from the sides and drag chains 19 are secured to these ears and are operated in the usual manner.

With this structure the earth is cut and rolled up into the scraper. The arch is very much stiffened and also the rear wall and a much wider drag link is feasible than with the ordinary construction. The channel form along the top makes a simple, yet very rugged construction for the wall.

What I claim as new is:

1. A power scraper having side walls and a connecting rear wall, said scraper being open at its bottom; an arch connecting the side walls; and a rigid connection comprising a vertically extending web between the arch and the rear wall.

2. A power scraper having side walls and a connecting rear wall, said scraper being open at its bottom; and a dividing plate extending from the rear wall between the side walls and dividing the scraper into two compartments.

3. A power scraper having side walls and a connecting rear wall, said scraper being open at its bottom; a dividing plate extending from the rear wall between the side walls and divid-

ing the scraper into two compartments; and an arch connecting the side walls, said arch being connected with the dividing plate.

4. A power scraper having side walls and a connecting rear wall, said scraper being open at its bottom; and laterally extending shoes projecting inwardly from the lower edges of the side walls, said shoes terminating in forwardly and laterally outwardly extending points at their forward ends.

5. A power scraper having side walls and a connecting rear wall; a forwardly extending dividing plate; and laterally extending shoes projecting inwardly from the side walls and dividing plate.

6. A power scraper having side walls and a connecting rear wall, said scraper being open at its bottom; a forwardly extending dividing plate; and laterally extending shoes projecting inwardly from the side walls and dividing plate, said shoes terminating in points at their forward ends.

7. A power scraper having side walls and a connecting rear wall; a forwardly extending dividing plate; and laterally extending shoes projecting inwardly from the lower edges of the side and rear walls and the dividing plate.

8. A power scraper having side walls and a connecting rear wall; a forwardly extending dividing plate; and laterally extending shoes projecting inwardly from the lower edges of the side and rear walls and the dividing plate, and terminating in points at their forward end.

9. A power scraper having side walls with a connecting rear wall; a forwardly projecting dividing plate; and laterally extending shoes projecting from the lower edge of the dividing plate.

10. A power scraper having side walls with a connecting rear wall; a forwardly projecting dividing plate; and laterally extending shoes projecting from the lower edge of the dividing plate and terminating in a point at its forward end.

11. A power scraper comprising side walls and a connecting rear wall; a forwardly projecting dividing plate; laterally extending shoes projecting inwardly from the lower edges of the side and rear walls and dividing plate, said shoes terminating in points at their forward ends; an arch connecting the sides; and a connection between the arch and the plate.

55 In testimony whereof I have hereunto set my hand.

LEWIS E. YOUNIE.
